NOISE REJECTING LIMITER SYSTEM

Vernon D. Landon, Haddonfield, N. J., assignor
to Radio Corporation of America, a corpora-
tion of Delaware

Application July 30, 1938, Serial No. 222,141

8 Claims. (Cl. 179—171)

This invention relates to noise rejecting limiter systems such as are utilized to eliminate undesired electrical impulses from the output of radio receiver apparatus or the like, and has for its 5 principal object the provision of an improved system and method of operation whereby the signal output of the system is reduced to a low value or to zero in response to received impulses exceeding a predetermined level.

10 A distinguishing characteristic of the invention is the use of an electron discharge device which is provided with a cathode lead resistor and is operated with relatively high screen grid and relatively low anode voltages. Under these conditions, the signal input is amplified and the signal output increases up to a predetermined signal input level, after which it decreases due to the cathode resistor drop which renders the cathode potential more positive than that of the anode.

15 It will become apparent that, although the control grid of the electron discharge device swings positive with respect to ground, the control grid does not draw current because at the same time the cathode is subjected to a positive potential.

20 It will become apparent that, although the control grid of the electron discharge device swings positive with respect to ground, the control grid does not draw current because at the same time the cathode is subjected to a positive potential.

25 In the operation of this system at high radio frequencies, it is found that the cathode voltage may lag due to the cathode capacity, and less efficient rejection of strong noise impulses may be thus produced. This difficulty is avoided by 30 tuning out the cathode capacity by means of a cathode to ground inductor or the like, a capacitor being connected in series with the inductor to prevent short-circuiting the direct current component through the cathode resistor.

35 While the system so far described functions during the signal rejecting period with an output current which is very low and represents a relatively small percentage of the signal carrier fundamental, this output current may be readily 40 caused to assume a substantially zero value during the signal rejecting periods. One suitable method of accomplishing this result is to interconnect the cathode and anode of the electron discharge device through a resistor or the equivalent, and to apply the signal to the electron discharge device input circuit through an amplifier which also 45 functions as an anode current cut-off limiter. As will be understood, the electron discharge device or rejector limiter is especially useful in connection with high radio frequency currents for the reason that only relatively low impedances are involved.

The invention will be better understood from 55 the following description, considered in connec-

tion with the accompanying drawings, and its scope is indicated by the appended claims.

Referring to the drawings:

Figure 1 is a wiring diagram of a radio receiver to which the invention has been applied.

Figure 2 is a wiring diagram of the electron discharge device or rejector limiter which is included in the system of Fig. 1.

Figure 3 illustrates the static grid voltage-plate current characteristic of the device of Fig. 2, 10

Figure 4 illustrates the radio frequency input-output characteristic of the device of Fig. 2,

Figure 5 illustrates the rejector limiter as fed through a plate cut-off limiter and as provided with a cathode-anode resistor for minimizing the 15 carrier fundamental component in the output circuit during the rejection periods,

Figures 6 and 7 are explanatory curves relating to the operation of the system of Fig. 5, and

Figure 8 illustrates the cathode to ground 20 resistor as shunted by a reactor for neutralizing the cathode capacity of the rejector limiter.

The radio receiver of Fig. 1 includes an antenna 25 10, a plurality of wave traps 11, 12 and 13, a broadly tuned radio frequency channel section including the amplifier stages 14 and 15, a rejector limiter 16, a sharply tuned radio frequency channel section including amplifier stages 17 and 18, a detector 19, an audio frequency channel section including amplifier stages 20 and 21, and a loud 30 speaker 22.

As stated in my copending application Serial No. 210,581, filed May 28, 1938, and assigned to the same assignee as the present application, it is desirable that the amplifier stages preceding 35 a limiter be broadly tuned and that the amplifier stages following the limiter be sharply tuned. In order to avoid the application to the limiter of broadcast signals from stations adjacent to the desired station, it is proposed by the aforesaid application to interpose in the antenna output leads a plurality of wave traps which are so ganged or mechanically coupled with the tuning elements of the sharply tuned radio frequency channel section that each unwanted broadcast 40 signal is prevented from reaching the input of the broadly tuned channel section, thus allowing the broadly tuned channel section ahead of the limiter to cover the full width of the broadcast band except for the signal ranges excluded by the 45 wave traps.

Insofar as the wave traps 11, 12 and 13, the broadly tuned channel section 14 and 15, and the sharply tuned channel section 17 and 18 are concerned, the radio receiver of Fig. 1 is similar 55

to that of the aforesaid application. Thus, in both cases, the wave trap switching means and the sharply tuned channel section and detector tuning elements are so controlled by a single member (23 in the present application) as to minimize the unwanted broadcast signals which would otherwise pass through the broadly tuned channel section and tend to saturate the limiter.

Power for operating the receiver of Fig. 1 is derived from a suitable direct current source, shown as a bleeder resistor 24 provided with terminals 25 to 29 from which different voltages are applied to the various electrodes of the different stages.

15 It should be particularly noted that the anode 30 of the rejector limiter 16 has a relatively low voltage applied to it through the terminal 28, that a relatively high voltage is applied to the screen grid 31 of the limiter 16 through the terminal 27, and that an unbypassed resistor 32 is connected between the limiter cathode 33 and the ground terminal 29. Signal impulses are applied to the control grid 43 of the limiter through a coupling transformer and the limiter output is supplied to the sharply tuned channel section through a coupling transformer 35, the suppressor grid 36 of the limiter 16 being connected to the low voltage primary terminal of the transformer 35 to afford a screening action which somewhat increases the output current.

30 As indicated more particularly in Fig. 2, the resistor 32 may have a resistance of the order of 6000 ohms, the potential applied to the screen grid 31 may be of the order of 37 volts, and the potential applied to the anode 30 may be of the order of 6 volts. While these values have been found to give satisfactory results, it should be understood that they are not critical, but may be varied to suit the conditions under which the rejector limiter 16 is operated.

35 The static grid potential-output current characteristic of the rejector limiter 16 is indicated by Fig. 3. It is desirable that the operating bias be such as to produce operation at the center of the positive slope of the curve as indicated by the line 37. In the operation of the system, a bias potential measured from grid to ground of the order of zero volts is found to be satisfactory, although this value is not critical, but may be varied to suit different operating conditions.

40 As the grid potential is made more positive the plate current increases in the normal manner until the cathode potential approaches and passes the plate potential, at which point the plate current decreases becoming and remaining substantially zero for large positive grid excursions. The screen current continues to rise for positive grid voltages. The current which would ordinarily go to the plate goes to the screen instead, when the cathode becomes positive with respect to the plate.

45 The grid is never positive with respect to the cathode in the region of the curve illustrated in Fig. 3. The abscissa is the voltage from grid to ground.

50 As indicated by the RF input-RF output characteristic of Fig. 4, the rejector limiter 16 output increases up to the point 38, and thereafter rapidly decreases to a relatively low value, due to the cathode being driven more positive by the increased potential drop of the resistor 32. While the rejector limiter output at the fundamental frequency of the carrier does not attain a zero value, this small percentage of fundamental frequency may not be objectionable in some cases.

If desired, it may be eliminated by modifying the rejector limiter connections, as shown by Fig. 5.

5 In this modification, a resistor 44, connected between the anode 30 and the cathode 33 of the rejector limiter 16, serves to feed into the limiter output circuit a potential whereby the fundamental component is reduced to zero or completely cancelled in the limiter output circuit.

10 Thus, as indicated by the input-output characteristic of Fig. 6, the fundamental component of the output is reduced to zero in the region of the point 45 and tends to rise with increased input, as indicated by the broken line section 46.

15 This rise in the fundamental component with increased output, however, may be prevented by interposing between the broadly tuned channel section output and the rejector limiter 16 a plate current cut-off limiter which is provided with a cathode resistor 48 and is coupled to the control 20 grid 43 of the limiter 16 through resistors 49 and 50 and a capacitor 51.

25 The various electrical relations involved under these conditions are more clearly indicated by the curves of Fig. 7 which, taken with the accompanying legends, are self-explanatory. It will be noted that the full line "Plate current" curve indicates the presence of a fundamental component for the reason that the peaks are unevenly spaced, and that this condition is corrected by the broken line modification of the 30 full line curve, the broken line parts indicating how the full line plate current curve is modified by the insertion of the resistor 44. Otherwise stated, the resistor 44 so modifies the plate current wave shape that the fundamental of the carrier voltage applied to the grid 43 is completely cancelled during the rejection period.

35 When operated at high or radio frequencies, the cathode voltage of the rejector limiter 16 tends to lag because of cathode capacity. This is likely to result in less efficient rejection of strong noise impulses. This difficulty is avoided by connecting across the resistor 32 (Fig. 8) an inductor 47, a by-pass capacitor 48 being serially connected with the inductor to prevent short-circuiting the resistor 32 to the direct current component.

40 While the combination of the electron discharge device 16 with the cathode resistor 32, and with the use of a relatively high voltage on the screen grid and a relatively low voltage on the anode, has been described in various environments, it will be apparent that this combination has other uses and that its novelty is 55 not restricted to these particular environments.

45 I claim as my invention:

1. The combination of an electron discharge device including a cathode, an anode and a plurality of grids, means for applying electrical impulses to one of said grids, means for applying a relatively low potential to said anode, means for applying a relatively high potential to another of said grids, and a resistor connected in series with said cathode whereby the cathode-anode current of said device is reduced when the level of said impulses increases above a predetermined value.

50 2. In the operation of an electron discharge device provided with a cathode, an anode, a plurality of grids and a cathode lead resistor, the method which includes applying electrical impulses to one of said grids, applying a relatively low potential to said anode, and applying a relatively high potential to another of said grids

whereby the cathode-anode current of said device is reduced when the level of said impulses increases above a predetermined value.

3. The combination of an electron discharge device including a cathode, an anode and a plurality of grids, means for applying electrical impulses to one of said grids, means for applying a relatively low potential to said anode, means for applying a relatively high potential to another of said grids, a resistor connected in series with said cathode, and means for minimizing the fundamental frequency component of said impulses in the current delivered from said cathode and anode, when said impulses exceed a predetermined value.

4. The combination of an electron discharge device including a cathode, an anode and a plurality of grids, means for applying electrical impulses to one of said grids, means for applying a relatively low potential to said anode, means for applying a relatively high potential to another of said grids, and a resistor connected between said cathode and anode for minimizing the fundamental frequency component of said impulse in the current delivered from said cathode and anode, when said impulses exceed a predetermined value.

5. The combination of an electron discharge device including a cathode, an anode and a plurality of grids, means for applying electrical impulses to one of said grids, means for applying a relatively low potential to said anode, means for applying a relatively high potential to another of said grids, a resistor connected in series with said cathode, and means connected in shunt to said resistor for neutralizing the capacity effect of said cathode.

6. The combination of an electron discharge

device including a cathode, an anode and a plurality of grids, means for applying electrical impulses to one of said grids, means for applying a relatively low potential to said anode, means for applying a relatively high potential to another of said grids, a resistor connected in series with said cathode, and means including an inductor connected in shunt to said resistor for neutralizing the capacity effect of said cathode.

7. The combination of an electron discharge device provided with an anode, a plurality of grids, a cathode and an impedance device connected in the lead of said cathode, means including a plate cut-off limiter for applying electrical impulses to one of said grids, means for applying a relatively low potential to said anode, and means for applying a relatively high potential to another of said grids whereby the cathode-anode current of said device is minimized when the level of said impulses attains a predetermined value.

8. The combination of an electron discharge device provided with an anode, a plurality of grids, a cathode and an impedance device connected in the lead of said cathode, means including a plate cut-off limiter for applying electrical impulses to one of said grids, means for applying a relatively low potential to said anode, means for applying a relatively high potential to another of said grids, and means for balancing out of the current delivered from said cathode and anode the fundamental frequency component of said impulses, whereby said current is interrupted in response to a predetermined level of said impulses.

VERNON D. LANDON.
